DESIGN FOR A COMBINED BOOKMARK AND GREETING CARD

Jack V. Scott, Philadelphia, Pa.

Application June 9, 1945, Serial No. 120,001

Term of patent 14 years

(Cl. D59—2)

To all whom it may concern:

Be it known that I, Jack V. Scott, a citizen of the United States, residing at Philadelphia, in the county of Philadelphia and Commonwealth of Pennsylvania, have invented a new, original, and ornamental Design for a Combined Bookmark and Greeting Card, of which the following is a specification, reference being had to the accompanying drawing forming a part thereof, in which

I claim:

The ornamental design for a combined bookmark and greeting card, substantially as shown.

JACK V. SCOTT.
